UNITED STATES PATENT OFFICE.

JOSEPH ULRICH, OF BEARDSLEY, MINNESOTA.

BACK-PAD.

1,088,382.

Specification of Letters Patent. Patented Feb. 24, 1914.

Application filed May 28, 1913. Serial No. 770,423.

To all whom it may concern:

Be it known that I, JOSEPH ULRICH, a citizen of the United States, residing at Beardsley, in the county of Bigstone and State of Minnesota, have invented certain new and useful Improvements in Back-Pads, of which the following is a specification, reference being had to the accompanying drawings.

10 This invention relates to new and useful improvements in harness and more particularly to a back pad therefor and my object is to provide a device of this character which will enable the harness to be readily and 15 quickly applied and removed, when desired.

A further object of the invention resides in providing a back pad provided with means for guiding the back straps therethrough, said means being such as will permit said 20 back straps to be readily and quickly removed from the horse without detaching the same from the hames.

25 A further object of the invention resides in providing a device which is simple and durable in construction, inexpensive to manufacture and one which will be very efficient and useful in operation.

With these and other objects in view, the 30 invention consists in the novel features of construction, combination and arrangement of parts as will be hereinafter referred to and more particularly pointed out in the specification and claim.

35 In the accompanying drawing forming a part of this application, Figure 1 is a perspective view of the device showing the same applied to use. Fig. 2 is a vertical section through the device.

40 In describing my invention, I shall refer to the drawing in which similar reference characters designate corresponding parts throughout the several views and in which—

1 indicates a base plate of a particular design and formed of leather, the under face 45 of which has a felt strip 2 suitably secured thereto and this base plate is adapted to be applied to the back of an animal. Riveted or otherwise similarly secured to the top face of said base 1, to extend the full length 50 thereof and project beyond the ends of the same, is a strap 3. The projecting portions of the strap 3 extend through and are suitably engaged with buckles 4, which are of a well known type, the portions continuing 55 from said buckles being looped, as shown at 5 and the extreme free ends of said strap

are drawn into engagement with said buckles. These looped portions 5 afford engaging means for the traces 6 which extend therethrough and in view of the particular 60 means of securing the strap to the buckles, these traces may be readily and quickly engaged or disengaged, when desired.

Superimposed on the strap 3 and secured thereto by a portion of the same means 65 which secures said strap to the base plate 1, is an additional strap 7, the ends of which extend to points a short distance on each side of the center of said base plate 1. The free ends of this additional strap are engaged 70 with additional buckles 8, similar to the buckles 4 and also superimposed on the strap 3, adjacent the ends of the base 1, and secured thereto by a portion of the means which secures said strap to said base, are the 75 additional straps 9. These latter straps are secured in position adjacent their outer ends and their inner opposed ends are adapted to be suitably engaged with the buckles 8, with which the ends of the strap 7 are also engaged. 80 The securing or the ends of the strap 7 and the straps 9 together, through the medium of the buckles 8, provides loops or guides 10 through which the back straps 11 of the harness are disposed. Thus, when 85 it is desired to unhitch the horse, the back straps may be disengaged from the back pad by merely disengaging the straps 7 and 9 from the buckles 8, without entirely disengaging said back straps from the hames. 90 In view of the particular construction of the buckles 8, the straps 7 and 9 may be quickly and readily disengaged.

From the foregoing description of the construction of my improved device, the 95 manner of applying the same to use will be readily understood and it will be seen that I have provided a device which is simple and durable in construction, inexpensive to manufacture and one which will be very efficient and useful in operation.

While I have particularly described the elements best adapted to perform the functions set forth, it is obvious that various changes in form, proportion and in the 105 minor details of construction may be resorted to without departing from the spirit or sacrificing any of the principles of the invention.

Ordinarily when harness is oiled, the oil 110 is apt to flow through the pad and in the use of the latter, cause the hair on the horse's

back to be worn. With my device, however, the parts of the harness to be oiled may be quickly and readily detached for this purpose and the liability of the oil reaching or flowing to the horse's back is thereby obviated.

Having thus described this invention, what is claimed is:—

In a device of the class described, a base plate, a strap secured on the outer face of said plate and projecting beyond the ends of the latter, the projecting ends of said strap being looped to provide means for engagement with traces, buckles suitably securing the extreme free ends of the last mentioned strap to the body portion thereof, a second strap superimposed on the first mentioned strap and secured to the latter by the same means securing said first mentioned strap to the base plate, the ends of said second mentioned strap being free, a pair of ad-

ditional straps superimposed on the first mentioned strap and secured adjacent their ends to the first mentioned strap at points adjacent the projecting portions thereof, said additional straps being secured to the first mentioned strap by a portion of the same means which secures the latter to the base plate, and additional buckles adjustably securing the free ends of said additional straps to the free ends of the second mentioned strap, thereby providing guide loops upon opposite sides of the center of the base plate for the reception of back straps therethrough.

In testimony whereof I hereunto affix my signature in the presence of two witnesses.

JOSEPH ULRICH.
